UNITED STATES PATENT OFFICE

CHARLES C. GATES, OF DENVER, COLORADO

DISPLAY BRACKET

Application filed July 28, 1928. Serial No. 294,774.

This invention relates to improvements in display devices and has reference more particularly to an improved bracket which can be employed for the display of automobile accessories.

It is customary to provide the trade with radiator hose in lengths of about three feet, from which the dealer may cut a length suitable for the particular car for which the connection is to be used. As there are several different types of automobiles and many of them require radiator hose connectors of different diameter, it is necessary for the dealer to carry an assortment of radiator hose.

For the purpose of supporting these lengths of radiator hose in a convenient way and so that the stock on hand can be readily determined by an inspection, I have produced a display device comprising a bracket consisting of two separable parts, one of which is a base, which is adapted to be secured to a wall or other supporting member and whose rear surface is provided with a depressed area having an opening, the other part consisting of a substantially straight supporting arm of such size that it can be passed through the opening and whose rear end is slightly enlarged and bent at right angles so as to lie in the depressed area between the base and the supporting surface. This supporting arm may be provided with holes from which are supported rods that are provided at their ends with hooks, these rods are slightly longer than the radiator hose and are inserted through the latter, the hose being supported by the hook at the lower end of the rod. Brackets of this type can be taken apart and packed into a small space for shipment and can be readily assembled and applied to the supporting surface without the use of any special tools.

In order to more clearly describe the invention so that its construction and mode of operation can be more readily understood, reference will now be had to the accompanying drawing, in which the preferred embodiment thereof has been illustrated, and in which:

Fig. 1 is a perspective view of my in-

proved bracket showing the same as it appears when in use;

Fig. 2 is a plan view of the plate forming the base of the bracket;

Fig. 3 is a section taken on line 3—3, 55 Fig. 2;

Fig. 4 is a section taken on line 4—4, Fig. 2; and

Fig. 5 is a section taken on line 5—5, 60 Fig. 1.

In the drawing numeral 1 represents a base plate which is formed from sheet metal and which has been shown as having its upper and lower edge parallel, the lower edge being shorter than the other and the 65 sides of the plate being formed by angularly related lines so that the upper half of the plate is rectangular and the lower half of the plate being a trapezoid. The edges of the plate which have been indicated by numeral 2 are curved rearwardly in the manner shown in Figs. 3 and 5, so that they lie in a plane parallel with but spaced from the rear surface of the plate. This tends to strengthen the plate and to make it fit 75 more readily against the supporting surface which has been designated by numeral 3. The rear surface of the plate is provided with a depression 4, which is substantially rectangular and which is provided at one 80 side with an opening 5. In the example shown this opening is located on the median line of the base plate near the lower end of the depressed area which, as shown in Fig. 2, is located on one side of the median line. 85 The base plate is also provided with two openings which have been designated by reference numeral 6 and which are located equal distances from the median line near the upper end of the plate. The outer edges of 90 these openings are pressed outwardly in the manner indicated by numeral 7, so as to make it more convenient to insert a paper tag 8 in the manner shown in Fig. 5. These paper tags may contain the size or any other 95 information relating to the object displayed. The other part of the bracket consists of a supporting arm 9 which is formed from sheet metal of slightly greater thickness than that employed for the base and whose outer 100

end terminates in an upwardly extending point 10, which serves to prevent the accidental displacement of articles supported thereon. The other end is provided with an extension 11 which forms with the end of the supporting arm a rectangular portion which has been designated as a whole by reference numeral 12 and which is bent at right angles to the plane of the arm 9 in the manner shown quite clearly in Figs. 3 and 4. When the arm is inserted through the opening 5, from the back of the plate, the enlarged portion 12 will fit the depressed area. The depression has such a depth computed to the thickness of the material of the part 12 and the distance from the back surface of the plate to the edges 2 that when the base plate is secured to a flat supporting surface, the part 12 will fit snugly between the rear surface of the depressed portion and the supporting surface, so that when the bracket is secured to a flat supporting surface by means of screws 13 the supporting arm 9 will be held firmly in the position shown in Fig. 1. When the bracket is to be used for supporting radiator hose of the type indicated by reference numeral 14, the supporting arm is provided with a plurality of openings 15, to which the supporting rod 16 may be attached. This supporting rod or rods is provided at the upper end with a hook 17, that can be inserted through one of the openings 15 and at the lower end with a hook 18, which is adapted to receive the wall at the lower end of the hose. The length of the rod is such that the hose 14 can be raised upwardly a sufficient distance to unhook it from the lower end of the rod. In the drawing I have shown only one supporting rod and one radiator hose connected to the supporting arm, but two or more may be supported from each arm if desired. I have also indicated in Fig. 1 how the supporting arm can be employed for the support of fan belts 19 and similar articles.

From the above description it will be apparent that I have produced a bracket of very simple and substantial construction that can be readily taken apart for packing when it is shipped and which can be readily assembled at its point of destination. This bracket is formed of two stampings which makes it very cheap to make and is so constructed that it can be applied to the supporting surface without the use of any special tools, as it requires only a screw-driver for this purpose.

I want to call particular attention to the construction of the plate and the supporting arm, by means of which a quite rigid assembly can be formed when the bracket is put into operative position.

Having described the invention what is claimed as new is:

1. A display device comprising a two-part bracket, one part of which is a plate adapted to be secured to a flat supporting surface and provided on the side nearest the supporting surface with a depressed portion having an opening, the other part consisting of a supporting bar extending through the opening and having one end provided with an enlarged part bent into a plane at right angles to the main portion and adapted to lie in the depression. 70 75

2. A two-part bracket comprising a plate adapted to be secured to a supporting surface, said plate having a depressed portion in its rear surface, said depressed portion having an opening, an elongated supporting bar having a substantially straight portion provided at one end with an enlarged portion bent at right angles to the bar and adapted to lie in the depression, the straight portion extending through the opening and extending substantially perpendicular to the plane of the plate. 80 85

3. A two-part bracket comprising a plate adapted to be secured to a supporting surface, said plate having a depressed portion in its rear surface, said depressed portion having an opening, the edges of said plate being bent rearwardly and terminating in a plane lying a short distance to the rear of the plane of the rear surface of the plate, a supporting bar comprising a straight narrow member which extends through the opening in the plate, one end of the bar being bent at right angles to the plane of the bar and lies in the depression. 90 95 100

4. A two-part bracket comprising a plate adapted to be secured to a supporting surface, said plate having a depressed portion in its rear surface, said depressed portion having an opening, the edges of said plate being bent rearwardly and terminating in a plane lying a short distance to the rear of the plane of the rear surface of the plate, a supporting bar comprising a straight narrow member which extends through the opening in the plate, one end of the bar being bent at right angles to the plane of the bar and lies in the depression, said plate being also provided with openings for screws by means of which it is fastened to a support. 105 110 115

5. A bracket comprising a plate having its edges curved rearwardly so that they lie in a plane parallel to the plane of the rear surface, the rear surface having a depressed area, the depressed area having an opening at one side, a supporting bar having a straight portion extending through the opening, one end of said bar being wider than the bar and bent at right angles, said last named portion lying in the depression and serving to anchor the supporting bar to the plate. 120 125

6. A bracket comprising a plate having 130

its edges curved rearwardly so that they lie in a plane parallel to the plane of the rear surface, the rear surface having a depressed area, the depressed area having an opening at one side, a supporting bar having a straight portion extending through the opening, one end of said bar being wider than the bar and bent at right angles so as to provide an anchor adapted to fit the recess, said plate having openings for the reception of screws by means of which it is attached to a support.

7. A bracket comprising a plate having its edges curved rearwardly so that they lie in a plane parallel to the plane of the rear surface, the rear surface having a depressed area, the depressed area having an opening at one side, a supporting bar having a straight portion extending through the opening, one end of said bar being wider than the bar and bent at right angles so as to provide a part adapted to fit the recess, said plate having openings for the reception of screws by means of which it is attached to a support, and spaced parallel openings adapted to receive the ends of a tag.

In testimony whereof I affix my signature.
CHARLES C. GATES.
